UNITED STATES PATENT OFFICE.

CHARLES RADIGUER, OF ST.-DENIS, FRANCE, ASSIGNOR TO THE SOCIETE ANONYME DES ETABLISSEMENTS DELAUNAY-BELLEVILLE, OF ST.-DENIS, FRANCE, A CORPORATION OF FRANCE.

AIR-SUPPLYING MEANS FOR LIQUID-FUEL BURNERS.

1,163,108.

Specification of Letters Patent.

Patented Dec. 7, 1915.

Application filed June 18, 1914. Serial No. 845,878.

To all whom it may concern:

Be it known that I, CHARLES RADIGUER, citizen of the French Republic, residing at St.-Denis, Department of the Seine, in France, have invented certain new and useful Improvements in Air-Supplying Means for Liquid-Fuel Burners; and I do hereby declare the following to be a full, clear, and exact description of the invention, such as will enable others skilled in the art to which it appertains to make and use the same.

The air necessary for the combustion of petroleum and other liquid fuels, must reach the furnace intimately mixed with the petroleum. When the liquid is injected in the form of a conical sheet finely atomized, the mixing is effected by means of air injecting drums or twyers completely surrounding the atomizer.

Good results are obtained if a movement of rotation about the axis of the atomizer is imparted to the air. To this end the drums have been provided with directing blades similar to those of a radial turbine or of a centrifugal fan. This system has one drawback: it does not permit of reducing the section of the passage for the air when the activity of combustion diminishes. In order to eliminate this drawback, it has already been proposed to surround the drum with a sheath movable parallelly to the axis, permitting of the air passages being closed completely or to a greater or lesser extent. This system, however, doubles the size of the drum because the sheath must be as long as the drum so as to insure a complete closure, while its own length is added to that of the drum when it is in the fully closed position; moreover, this system is only applicable to cylindrical drums and not to truncated drums which are frequently used.

In the arrangement according to the invention a drum is used, the directing blades of which are movable after the manner of Venetian blinds. The movement of the blades may be effected positively; in this case, the drum must be arranged within a casing communicating with the air heating apparatus through doors shutting automatically in the case of flame returns. The movable blades may also be controlled by mechanism which resists the opening, but

not the closing movement so that they shut automatically in the case of a flame return.

In the accompanying drawings: Figures 55 1 and 2 refer to the first method of controlling. Figs. 3 and 4 to the second method. Fig. 1 is a vertical section on line X—X of Fig. 2. Fig. 2 is a vertical section on line Y—Y of Fig. 1. Fig. 3 is a vertical section on line Z—Z of Fig. 4. Fig. 4 is a vertical section on line T—T of Fig. 3.

Referring to Figs. 1 and 2, on the facing 1 of the boiler, is mounted a drum, denoted generally by the reference character 2, and which is formed by the various devices hereinafter described for supplying air to the burner. The drum is located in a rectangular box 3 into which air is introduced under pressure from the heating apparatus. The box 3 is provided with a door 4¹, 4² adapted to oscillate about a hinge 5; this hinge is arranged in such a manner that the two portions 4¹, 4² have unequal areas. The lower portion 4¹ is weighted in any suitable manner to retain the larger portion at the top. In the case of a flame return, it will be seen that it would act directly on the large surface 4² of the door and shut the latter.

The burner designated by 6 is mounted concentrically with the drum 2. Within this drum, a disk 7 is freely mounted on the rim 8 between the guide 9 and the annular plate 10. The latter and a similar one 10¹, are connected by the spacing rods 11—11, 11 which carry, freely mounted thereon, the angle pieces 12—12, upon which the blades 13—13 are mounted.

The oscillation of the angle pieces and therefore of the blades is effected by the simultaneous displacement of the tappets 14—14 mounted on the disk 7, and engaging notches formed in the angle pieces 12—12. A nut 15 is pivotally connected to the disk 7 by means of a tube 16 movable in an opening formed in the face of the drum 2; this nut receives a screw 17 which rotates without advancing in a pivotal connection 18 mounted on the facing of the said drum, and which is actuated by means of the hand wheel 19 to control the passage of air.

Referring to Fig. 2, the blades 13 are in their extreme position of opening; by push-

ing the nut 15 to the left, the passage of the air between the blades is diminished, and when the nut is at the end of its travel, the blades bear against one another and the passage of air ceases. A vertical pointer not shown on the drawing, but which may be integral with the nut 15 indicates by its rectilinear displacement on the front face of the casing, the degree of opening of the passages. With this arrangement a flame return cannot cause the closure of the blades, but the door 4¹, 4² will close and thus interrupt any communication between the furnace and the heating apparatus, the door remaining subsequently under the pressure of the compressed air of the said apparatus.

Referring to Figs. 3 and 4, the drum 20—20, the front circular face of which is spaced from the boiler facing 1 by the spacing rods 20¹—20¹ is not located in a casing and the inclined blades 21—21 are directly acted upon by the compressed air of the air heating apparatus. These blades are pivoted at 22—22 and in the closed position each of them bears on the pivotal connection socket of its adjacent blade.

The pressure of the air of the heating apparatus causes the blades to open, the degree of opening being controlled by a notched disk 23 which rotates on a bearing 24 between two guides 25 and 26; the disk is formed with as many notches 23¹—23¹ as there are blades 21—21 and each of these notches serves as a stop for these blades which the compressed air of the heating apparatus drives. A movement of rotation of the disk 23 is produced by a mechanism comprising a screw, a nut and a pivotal connection 15, 16, 17, 18 and 19 as in Figs. 1 and 2. With this arrangement, if there is a flame return capable of driving back the com-

pressed air of the heating apparatus, the blades will immediately close all passages and prevent the flames from leaving.

I claim:

1. Air supplying means for fuel burners comprising a drum coaxially disposed with respect to the fuel burner and having a plurality of spacing rods running substantially parallel to the axis of the fuel burner and arranged in a circular series about said axis, an air-controlling blade pivotally mounted upon each of said rods, and means to adjust the positions of all of said blades, for the purpose described.

2. Air supplying means for fuel burners comprising a plurality of adjustable blades disposed substantially parallel with the axis of the burner and pivotally mounted in a circular series about the axis of the burner, and means to impart simultaneous movement to all of said blades, comprising a notched disk each tooth of which engages with one of said blades, and means to rotate said disk to adjust the positions of said blades.

3. Air supplying means for fuel burners comprising a plurality of adjustable blades disposed substantially parallel with the axis of the burner and pivotally mounted in a circular series about the axis of the burner, and means to impart simultaneous movement to all of said blades, comprising a rotatable disk, means to impart rotary movement thereto, and means whereby rotation of said disk simultaneously imparts movement to all of said blades.

In testimony whereof I affix my signature, in presence of two witnesses.

CHARLES RADIGUER.
